BAGGAGE RACK AND ATTACHING MEANS
THEREFOR

Carolus L. Eksergian, Media, Pa., assignor to The
Budd Company, Philadelphia, Pa., a corpora-
tion of Pennsylvania

Application February 12, 1948, Serial No. 7,959

12 Claims. (Cl. 105—325)

1
The invention relates to baggage racks for passenger vehicles, such as bus and railway vehicles, and more particularly, to the structure of such racks and the manner of their securing to the vehicle body walls.

Such racks heretofore have been supported by brackets of substantially the width of the rack secured at their outer ends to the transverse members or carlines or posts of the vehicle body wall. This necessitated accurately transversely aligning the brackets with the carlines and made it difficult to assemble the baggage rack as a separate subassembly and then secure it in final assembly to the vehicle body wall.

It is an object of the invention to provide a baggage rack which may be readily assembled as a subassembly and then brought into final assembly relation with the side wall of the vehicle and readily secured in place regardless of any irregularities in the longitudinal alignment of the side wall carlines. Such irregularities are difficult to avoid under practical manufacturing conditions.

This and other and further objects and advantages and the manner in which they are attained will become evident from the following detailed description when read in connection with the drawings forming a part of this specification.

In the drawings,

Figure 1 is a fragmentary perspective view, with parts broken away and shown in section, showing the baggage rack of the invention applied to a railway car side wall;

Figure 2 is an exploded view showing, in reduced scale, a fragmentary part of the car side wall in sectional plan and the separate baggage rack subassembly in relation thereto prior to final assembly;

Figure 3 is a view similar to Figure 2 but showing the parts assembled;

Figure 4 is a fragmentary transverse vertical sectional view through the baggage rack and adjacent portions of the car side wall; and

Figure 5 is a detail view similar to Figure 3 showing a slight modification.

In accordance with the invention and as embodied in the showing in the drawings, the baggage rack designated 10 is preferably subassembled as a unit extending the greater portion of the length of a railway car vehicle, or if desired, into separate lengthwise aligned units each extending across a plurality of spaced carlines of the body side wall. In the drawings, the rack has been shown of a length extending

2
across at least three of the spaced carlines or posts designated 16.

The baggage rack subassembly comprises a stiff outer longitudinal member 11, shown in the drawings as an outwardly facing channel, and a similar inner longitudinal member 12, the bottoms of these channels 11 and 12 being interconnected by spaced transverse members 13 which also may be of channel section and strongly secured to the channels 11 and 12, as by welding. The hollow channel section longitudinal members provide longitudinal conduits for wiring, etc., and the inner channel is shown closed by a moulding strip 14 which may also extend outwardly to close most of the bottom of the baggage rack frame. The top of the frame may be closed by a longitudinally extending plate 15 extending transversely from the inner longitudinal member 12 almost to the outer member 11. The subassembly so constructed provides a stiff structure resistant against bending in its plane and also having considerable torsional stiffness.

As shown in the drawings, the body side wall, 25 with which the rack above described is associated, may comprise a framework consisting of longitudinally spaced carlines or posts 16 interconnected by longitudinally extending vertically spaced members 17 and 18 and reinforced by outer plating 19 and corrugated sheathing 20 and inner reinforcing plates 21 and 22, all in the vertical region of securement of the baggage rack.

As shown in Figures 2 and 3, the rack sub- 35 assembly is of a length to extend across at least three carlines or posts 16, the central one of which is shown of smaller area than the end posts, although it is to be understood that all might be of the same construction. It is to be understood also that the rack subassembly might extend over most of the length of the car body, if desired. To facilitate the securement of the baggage rack assembly 10 to the posts 16 of the side wall, upper and lower brackets 40 23 and 24 are provided to connect the upper and lower side walls of the channel members 11 to the posts 16. The brackets are preferably first rigidly secured to one of the side wall and baggage rack subassembly and then finally secured through a wide transverse overlapping engagement with the other, this arrangement enabling the brackets to secure the parts equally well irrespective of the slight longitudinal misalignment of the posts unavoidable under practical manufacturing conditions.

A preferred method of assembly is to secure the lower angular brackets 24 in place on the posts and at the same height for all the posts. This securing is preferably by bolts 25. Then the baggage rack assembly is brought down in engagement with the side wall until the lower side wall of channel 11 seats on the inwardly extending arm of the angular bracket 24. Aligned holes may now be drilled in the overlapping parts and they may be secured together by rivets 26. The upper angular bracket 23 may now be brought into place with its one arm overlapping the posts 16 and the other arm extending inwardly and overlapping the top side wall of the channel member 11. Aligned holes may now be drilled in the overlapping arm and post and these parts secured by bolts, as 25. Finally, the widely overlapping inwardly extending arm of bracket 23 and the upper side wall of channel member 11 may be secured together, as by welding. It will be understood that welding might also be utilized in connection with the lower bracket 24 instead of the rivets 26.

While the angular brackets 23 and 24, in the form of the invention illustrated in Figures 1 to 4, are shown as extending across a plurality of posts, and this is the preferred form, the form shown in Figure 5 may also be used. In this form, the brackets are separate brackets, as 23a, arranged only at the location of the posts and not extending between the posts.

With the arrangement shown and described, it will be seen that the wide overlap between the brackets 23 and 24 and the outer longitudinal member 11 of the baggage rack assembly takes care of all irregularities of longitudinal alignment of the posts, which results in greater spacing of some posts than others from the inner margin of member 11.

Also, once the baggage rack subassembly is assembled as described, the bolted connection with the posts permits of its ready detachment therefrom with the attached brackets with the assurance that the parts will realign in proper relation when again attached.

To complete the baggage rack after its main structure has been assembled with the side frame of the body as described, suitable upper and lower fairing strips 27 and 28, shown in full lines in Figure 1 and in dot-and-dash lines in Figure 4, are secured in place to merge the upper and lower plates 15 and 14 with the adjacent inner lining of the body wall, as indicated at 29. The joints between the fairing strips and the inner lining 29 may be covered by suitable trim strips 30.

While the invention has been herein described in connection with a detailed embodiment thereof, it will be understood that changes and modifications may be made by those skilled in the art without departing from the main features of the invention, and such changes and modifications are intended to be covered by the appended claims.

What is claimed is:

1. In a passenger vehicle body, a side wall having spaced vertical posts, a baggage rack of a length extending over a plurality of said posts, said baggage rack comprising an outer longitudinal member of hollow cross section and attaching means connecting said outer member to the posts irrespective of variations in spacing of the inner faces of the posts from the outer margin of said hollow section member, said attaching means having a laterally wide overlap with

either said posts or said member through which the parts are finally secured together irrespective of whether or not a gap exists between the respective posts and the outer longitudinal member of said rack.

2. In a passenger vehicle body, a vertically extending rigid side wall having spaced vertical posts, a baggage rack assembly comprising a transversely rigid frame including spaced inner and outer longitudinal members interconnected by spaced transverse members and said assembly being of a longitudinal extent overlapping at least three of the vertical posts of said side frames, and brackets connecting the outer longitudinal member of said rack assembly to said posts, said brackets having wide transverse overlaps with either the posts or the outer longitudinal member of the rack assembly through which overlaps the final connection of the rack assembly to the posts is effected, the width of said overlaps taking care of any variations in spacing between the inner faces of the overlapped posts and the outer edge of the baggage rack assembly.

3. In a passenger vehicle body, a side wall having spaced vertical posts, a rigid baggage rack structure of a length extending over a plurality of said posts, said baggage rack structure comprising an outer longitudinal member of hollow cross section and attaching means connecting said member to the spaced posts irrespective of such differences in spacing between the outer margin of said member and the respective posts as normally occur under practical manufacturing conditions, said attaching means being preliminarily located and secured to either said posts or said member and having wide lateral overlaps with either said member or said posts through which they are finally secured thereto.

4. In a passenger vehicle body, a rigid side wall structure having spaced vertical posts, a baggage rack structure assembled in subassembly and comprising a rigid frame including inner and outer longitudinal members interconnected by spaced transverse members, said rack structure being of a length overlapping a plurality of the vertical posts of said side wall structure and brackets connecting the outer longitudinal member of said rack structure to the posts of said side wall structure, said brackets being first rigidly secured to one of said structures and having wide transverse overlaps with the other of said structures, when the two structures are brought together in final assembly, through which overlaps the final connection of the structures is effected, the width of said overlaps taking care of any variations in spacing between the inner faces of the overlapped posts and the outer margin of said baggage rack structure.

5. In a passenger vehicle body, a lengthwise extending wall structure having spaced carlines, a baggage rack structure assembled in subassembly and comprising a rigid frame including inner and outer longitudinal members interconnected by spaced transverse members, said rack structure being of a length overlapping a plurality of said carlines when disposed in final assembly relation with said wall structure, and brackets connecting the outer longitudinal member of said rack structure to the carlines of said wall structure, said brackets being first rigidly secured to one of said structures and having wide overlapping engagement in a plane or planes extending transversely of said wall structure with the other of said structures when the two structures are

brought together in final assembly, through which overlapping engagement the final connection of the structures is effected, the width of said overlapping engagement being ample to take care of any variations in spacing between the inner faces of the overlapped carlines and the outer margin of said baggage rack structure.

6. In a passenger vehicle body, a lengthwise extending body wall structure having spaced carlines, a separately subassembled baggage rack structure comprising a rigid frame including an outer hollow section longitudinal member, said rack structure being of a length overlapping a plurality of said carlines when disposed in final assembly relation with said wall structure, and brackets connecting said longitudinal member of said rack structure with the carlines of said wall structure, said brackets being first rigidly secured to one of said structures and having wide overlapping engagement, in a plane or planes extending transversely of said wall structure, with the other of said structures when the two structures are brought together in final assembly, the final connection of said structures being effected through said overlapping engagement and the width of said engagement being sufficient to take care of any variations in spacing between the inner faces of the overlapped carlines and the outer margin of said longitudinal member of the baggage rack structure.

7. In a passenger vehicle body, a side wall having spaced posts, a baggage rack subassembly of a length extending over a plurality of said posts, said baggage rack having a rigid frame including an outer longitudinally extending member of outwardly facing channel cross section, and brackets connecting said member to the side wall posts, said brackets comprising an upper angular section member having its arms secured respectively to a post and the upper side wall of said longitudinally extending member and a lower similar section bracket secured through its arms respectively to a post and the bottom side wall of said longitudinally extending member.

8. In a passenger vehicle body, a lengthwise extending body wall structure having spaced carlines, a separately subassembled baggage rack structure comprising a rigid frame including an outer hollow section longitudinal member, said rack structure being of a length overlapping a plurality of said carlines when disposed in final assembly relation with said wall structure and brackets connecting said longitudinal member of said rack structure with the carlines of said wall structure, said brackets being rigidly secured to said carlines and having wide overlapping engagement with the top and bottom respectively of said member through which they are secured thereto, the width of said overlapping engagement permitting securement irrespective of vari-

ations in spacing between the respective carlines and the outer margin of said longitudinal member of the baggage rack structure.

9. A baggage rack subassembly of a length extending across at least three carlines of a body to which it is applicable comprising spaced inner and outer hollow section longitudinal members and spaced transverse members interconnecting said longitudinal members and forming therewith a rigid framework, the outer longitudinal member providing means through the instrumentality of which the subassembly may be secured to a vehicle body wall.

10. A baggage rack subassembly of a length extending across at least three carlines of a body to which it is applicable comprising spaced inner and outer hollow section longitudinal members and spaced transverse members interconnecting said longitudinal members and forming therewith a rigid framework, at least the inner of said longitudinal members providing a conduit for wires or the like associated with the baggage rack.

11. A baggage rack subassembly of a length extending across at least three carlines of a body to which it is applicable comprising spaced inner and outer hollow section longitudinal members and spaced transverse members interconnecting said longitudinal members and forming therewith a rigid framework, a cover panel closing most of the bottom of said framework, and a cover panel extending across the top of said framework from the inner longitudinal member to a point adjacent the outer longitudinal member.

12. A baggage rack subassembly of a length extending across at least three carlines of a body to which it is applicable comprising spaced inner and outer hollow section longitudinal members and spaced transverse members interconnecting said longitudinal members and forming therewith a rigid framework, the inner longitudinal member being an inwardly facing channel, and trim paneling closing said inwardly facing channel and a substantial portion of the top and bottom of the framework from said inner longitudinal member outwardly.
